(57) **ABSTRACT**

A doll assembly includes a base that has a top side. A set of legs is integrally attached to and extends upwardly from the top side. The set of legs has an upper end that is attached together. A torso section has bottom end and a top end. Each of a pair of arms is integrally attached to and extends away from the torso section. A neck is integrally attached to and extends upwardly from the top end. A first spring attaches the torso section to the set of legs such that the torso section is movable with respect to the set of legs. A head has a bottom side. A second spring attaches the neck to the head such that the head is movable with respect to the neck.

1 Claim, 3 Drawing Sheets

FIG.3

1
DOLL ASSEMBLY

BACKGROUND OF THE INVENTION

1. Field of the Invention

The present invention relates to doll devices and more particularly pertains to a new doll device that includes body parts that move and bob with respect to each other when the doll is moved.

2. Description of the Prior Art

The use of doll devices is known in the prior art. While these devices fulfill their respective, particular objectives and requirements, the need remains for a device that includes a torso section movably coupled to legs and a head that is movably coupled to the torso section so that the torso section moves with respect to both the head and the legs.

SUMMARY OF THE INVENTION

The present invention meets the needs presented above by including a torso section attached by springs to legs and a head so that the torso bobs and moves with respect the legs and the head. This action provides more of a dancing movement than simply a bobbing head as found in the prior art.

To this end, the present invention generally comprises a base that has a top side. A set of legs is integrally attached to and extends upwardly from the top side. The set of legs has an upper end that is attached together. A torso section has bottom end and a top end. Each of a pair of arms is integrally attached to and extends away from the torso section. A neck is integrally attached to and extends upwardly from the top end. A first spring attaches the torso section to the set of legs such that the torso section is movable with respect to the set of legs. A head has a bottom side. A second spring attaches the neck to the head such that the head is movable with respect to the neck.

There has thus been outlined, rather broadly, the more important features of the invention in order that the detailed description thereof that follows may be better understood, and in order that the present contribution to the art may be better appreciated. There are additional features of the invention that will be described hereinafter and which will form the subject matter of the claims appended hereto.

The objects of the invention, along with the various features of novelty which characterize the invention, are pointed out with particularity in the claims annexed to and forming a part of this disclosure.

BRIEF DESCRIPTION OF THE DRAWINGS

The invention will be better understood and objects other than those set forth above will become apparent when consideration is given to the following detailed description thereof. Such description makes reference to the annexed drawings wherein:

FIG. 1 is a schematic front perspective view of a doll assembly according to the present invention.

FIG. 2 is a schematic front cross-sectional view of the present invention.

FIG. 3 is a schematic cross-sectional view of the present invention.

2
DESCRIPTION OF THE PREFERRED EMBODIMENT

With reference now to the drawings, and in particular to FIGS. 1 through 3 thereof, a new doll device embodying the principles and concepts of the present invention and generally designated by the reference numeral **10** will be described.

As best illustrated in FIGS. 1 through 3, the doll assembly **10** generally comprises a base **12** that has a top side **14**. A set of legs **16** is integrally attached to and extends upwardly from the top side **14**. The set of legs **16** has an upper end **18** wherein each of the legs of the set is attached together. The set **16** preferably includes a pair of legs each having bottom portions **20** defining feet.

A torso section **22** has bottom end **24** and a top end **26**. Each of a pair of arms **28** is integrally attached to and extends away from the torso section **22**. The arms **28** preferably terminate with hands **30** being integrally attached thereto. The bottom end **24** of the torso section **22** has a well **32** extending upwardly therein. The well **32** preferably has a frusto-conical shape. A neck **34** is integrally attached to and extends upwardly from the top end **26**. A first spring **36** attaches the upper end **18** of the set of legs **16** to an interior surface of the well **32** such that the upper end **18** of the set of legs **16** is positioned within the well **32**. The first spring allows the torso section **22** to be movable with respect to the set of legs **16**. The first spring **36** is generally vertically orientated so that the torso section **22** extends upwardly from the set of legs **16**.

A head **38** has a bottom side **40**. The bottom side **40** has a hole **42** extending upwardly therein. The hole **42** preferably has a frusto-conical shape. The head **38** preferably includes a face and other details so that the head appears to be the head of a person. Ideally, the head **38** is oversized with respect to the torso section **22**. A second spring **44** attaches the neck **34** to an upper wall of the hole **42** such that the neck **34** extends into the hole **42** and the head **38** is movable with respect to the neck **34**. The second spring **44** is generally vertically orientated for the same reason as the orientation of the first spring **36**.

FIG. 3 depicts couplers **46** for attaching the springs **36, 44** to the body sections **16, 22, 38** of the doll assembly **10**. The couplers **46** have first ends **48** that are extended into the body sections of the doll assembly **10** and a second end **50** having a channel **52** therein for receiving an end of the springs **36, 44**. The channel **52** is arcuate so that the spring may be twisted into the channel **52**. The couplers **46** offer an efficient way of attaching the springs **36, 44** to the body sections while also allowing the body sections to be replaced or changed.

In use, the doll assembly **10** is stood in an upright position. When moved, the torso **22** and head **38** move with respect to each other and with respect to the set of legs **16**.

With respect to the above description then, it is to be realized that the optimum dimensional relationships for the parts of the invention, to include variations in size, materials, shape, form, function and manner of operation, assembly and use, are deemed readily apparent and obvious to one skilled in the art, and all equivalent relationships to those illustrated in the drawings and described in the specification are intended to be encompassed by the present invention.

3

Therefore, the foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention.

We claim:

1. A doll comprising:

- a base having a top side;
- a set of legs being integrally attached to and extending upwardly from said top side, said set of legs having an upper end being attached together;
- a torso section having a bottom end and a top end, a pair of arms being integrally attached to and extending away from said torso section, said a bottom end having a well extending upwardly therein;

10

5

4

a neck being integrally attached to and extending upwardly from said top end;

a first spring attaching said upper end of said set of legs to an interior surface of said well such that said upper end of said set of legs is positioned within said well and said torso section is movable with respect to said set of legs, said first spring being generally vertically orientated;

a head having a bottom side, said bottom side having a hole extending upwardly therein; and

a second spring attaching said neck to an upper wall of said hole such that said neck extends into said hole and said head is movable with respect to said neck, said second spring being generally vertically orientated.
